BLIND STITCH SEWING MACHINE

Harley C. Moulton, Maplewood, and Charles W. Mueller, St. Louis, Mo., assignors to Lewis Invisible Stitch Machine Company, St. Louis, Mo., a corporation of Maine

Application April 14, 1936, Serial No. 74,362

6 Claims. (Cl. 112—176)

This invention relates to new and useful improvements in sewing machines generally, although more particularly to those of the blind stitch type.

5 The principal object of this invention is to provide a novel means for driving the loop taker from the main shaft whereby the sewing zone will be spaced a considerable distance below said main shaft to thereby provide a maximum of work 10 clearance space.

With this and other objects in view which will more fully appear, the nature of the invention will be more clearly understood by following the description, the appended claims, and the several 15 views illustrated in the accompanying drawings.

The work support forms the subject matter of our copending application Serial No. 183,892, filed January 7, 1938. The sewing machine frame forms the subject matter of our copending application Serial No. 196,972, filed March 19, 1938.

In the drawings:

Figure 1 is a plan view of a sewing machine embodying the invention.

Figure 2 is a front elevation, parts being 25 broken away and in section.

Figure 3 is a vertical cross section taken on the line 3—3 on Figure 1.

Figure 4 is a vertical transverse section taken on the line 4—4 on Figure 1.

30 Figure 5 is a vertical cross section taken on the line 5—5 on Figure 2, the work support being in the normal elevated position.

Figure 6 is a detail view similar to Figure 5, the work support being shown depressed.

35 Figure 7 is a vertical transverse section taken on the line 7—7 on Figure 3.

Figure 8 is an inverted plan view of the work support.

Figure 9 is an enlarged detail sectional view 40 taken on the line 9—9 on Figure 8.

Figure 10 is a detail inverted plan view illustrating means for adjusting the tension of the spring which resists depression of the work support.

45 Figure 11 is an inverted plan view of the base.

Figure 12 is an inverted plan view of the work support mounting bracket per se.

Figure 13 is a rear elevation of the standard and arm per se.

50 Figure 14 is an inverted plan view of the sewing head per se.

Figure 15 is a rear view of the tensioning unit and its mounting.

55 Figure 16 is a vertical section taken on the line 16—16 on Figure 1.

Figure 17 is a fragmentary front elevation illustrating a knee-press equipment for depressing the work support.

Figure 18 is an inverted plan view illustrating the mounting of the knee-press equipment.

Figure 19 is a detail perspective view of the knee-press rod and crank lever dismounted.

Figure 20 is a detail vertical cross section taken on the line 20—20 on Figure 18.

Like reference numerals designate corresponding parts throughout the several figures of the drawings.

In the practical development of our invention, we construct the machine of independently 15 mountable and replaceable units. There is provided a base unit A, a standard and arm unit B, a forwardly extending arm or sewing head unit C, a work support mounting bracket unit D, and a work support unit E. We also provide a removable thread tensioning unit F which is pref- 20 erably supported on the sewing head unit C.

The base unit A is in the nature of a generally 25 rectangular flanged body 5 having apertured mounting lugs 6 by which the base may be secured upon a bench or table, and a rectangular opening 7 disposed at the point at which the standard and arm unit B is to be mounted on the base and defined by apertured corner lugs 8 by which the mounting of the standard and arm unit is facilitated.

The base unit A is provided with a front cut-out or recess 9 flanged by reinforce lugs 10 having formed therein horizontally aligned bearing bores. A bearing lug 11 is provided for facilitating the mounting of toggle links later to be referred to, and a clearance groove or recess 12 is provided for accommodating movement of the devices by which the toggle links are actuated. Another bearing lug 13 is provided for supporting a tension adjusting bar which cooperates 40 with the toggle positioning devices.

The standard and arm unit B includes a standard portion 14 and an overhanging arm portion 15, the former being provided at its lower end with a rectangular opening matching the opening 7 in the base and defined by tapped corner lugs 16 for receiving the screws 17 by which the base unit A and the unit B are secured together in assembled relation as shown in Figures 3 and 4 of the drawings. The standard portion 14 is 45 provided with a front opening 18 which is covered by a removably mounted plate 19 which is slotted for a purpose that will later become apparent.

The overhanging arm portion 15 is provided 50

with the usual main shaft bearings 20 in which the main shaft 21 is journaled, said shaft being equipped with the usual pulley wheel 22.

At its free end the arm 15 carries a mounting flange 23 through the medium of which the forwardly extending arm or sewing head unit C is removably mounted on said arm, and a centering sleeve boss 24 for facilitating the mounting of said unit C in proper relation upon the arm. The boss 24 is interrupted or cut out at one point as at 25 for a purpose that will be described later.

Within the arm the main shaft 21 carries an eccentric 26 and collar 27, the eccentric being connected by strap 28 and pitman 29 with one end of a bell crank lever 30 pivotally mounted on the shaft 31 supported as illustrated in Figure 3 in bearings provided therefor in the walls of the standard 14. The remaining arm of the bell crank has connected thereto a link 32 which projects through and works in the slot of the standard cover plate 19 for a purpose that will be described later.

The sewing head unit C carries the mechanism by which the stitches are formed. In this particular disclosure the machine is adapted for the formation of single thread chain stitches but it is to be understood that the invention is not limited to this specific form of stitch forming mechanism. The unit C includes a head casting 33 having flange extensions 34 adapted to be removably secured, through the medium of the screws 35, to the mounting flange 23 with which the standard and arm unit B is equipped.

The casting 33 is provided with a recess or bore 36 for snugly receiving or fitting upon the sleeve boss 24 extending from the overhanging arm 15. It will be observed by reference to Figures 2 and 3 of the drawings that the main shaft 21 projects into the interior of the casting 33.

The casting 33 is provided with an opening 37 which is located in alignment with the main shaft 21, and through which access may be had to certain transmission elements connected to the adjacent end of the main shaft. This opening is covered by a removable thread tensioning unit F as illustrated in Figures 2, 3, and 15. The unit F comprises a plate 38 of a size adapted to overlie and cover the opening 37. A post 39, which is attached to the plate 38, projects outwardly therefrom and carries thread tension discs 40. A thread guide 41 is clamped between the post and the plate. A flange lug 42 which is rigidly attached to the inner face of the plate 38 adjacent one side edge thereof through the medium of a bracket 42^a, cooperates with said side edge to receive therebetween the associated side edge of the opening 37. A latch 43 in the form of a bell crank lever is pivoted as at 44 to the inner face of the plate adjacent the other side edge thereof. This lever includes a horizontal arm which projects towards the lug 42 and a depending arm which terminates in a lug 45 adapted to overlie the adjacent side edge of the opening 37. A coil spring 46 is connected at one end to the horizontal arm of the lever 43 and at its other end to the bracket 42^a, and functions to urge the latching lug 45 outwardly. The outward movement of the lug 45 is limited by a stop 43^a, which is attached to the bracket 42^a, and is normally engaged by the horizontal arm of the lever 43, as shown in Figure 15. In order to remove the unit F, it is only necessary to move the same laterally until the lug 42 is free of the adjacent side edge of the opening 37 and then swing the unit outwardly. When replacing the unit, the

latch lug 45 is first engaged with the associated side edge of the opening 37, the unit moved laterally against the tension of the spring 46 until the lug 42 becomes seated in the opening, and upon release of the unit the latter will slide laterally in the opposite direction through the medium of the spring 46 until the lug 42 has been positioned in latched relation with the associated side edge of the opening.

The casting 33 is provided with front and rear bearings 47, 48 in which is rockably mounted a needle shaft 50. It will be observed by reference to Figures 1, 2 and 7 of the drawings that the needle shaft is disposed in the line of feed of the work or in right angular relation to the main shaft 21, and that its axis is disposed a considerable distance below that of the main shaft, as shown in Figure 2.

A stationary presser foot 51 is rigidly mounted on the forward end of the arm or casting 33 below the needle shaft 50 and is provided with a longitudinal opening 52 in which a top feed dog operates and through which a node of fabric is raised by a ridge-forming element in the usual manner.

The needle shaft 50 projects forwardly through the front end of the arm or casting 33 and has secured thereon a needle arm 53 to which a needle 54 is affixed and by which said needle is oscillated back and forth in a plane at right angles to the direction of feed of the work, or, in other words, in a plane parallel to the plane in which the axis of the main shaft lies. At its inner or rear end the needle shaft carries a crank 55 which is connected by a pitman 56 to an eccentric 57 secured upon the end of the main shaft 21 which projects into the arm or casting 33 as shown in Figures 3 and 7 of the drawings.

A 4-motion top feed dog 58 is removably secured as at 59 to the forward end of a feed bar 60. In order to impart to the dog 58 the desired lifting and lowering movements, the bar 60 is provided with a cam grooveway 61 into which a fixedly supported roller 62 projects, the roller being journaled on a pin which is adjustably supported as at 63 in a wall of the casting or arm 33, as shown in Figure 4 of the drawings.

In order to impart the feed travel movement to the feed bar 60, we provide an eccentric 64 which is encircled by a strap extension 65 of said arm and is fixed to and is rotatable with a stub shaft 66 having a bearing at one end in a cap 67 removably secured at 68 to the casting 33 and having its other end journaled in a bearing 69 formed in a rear arm extension 70 of the web 49.

Also fixed to the stub shaft 66 is a drunken cam 71 having a thrust rod connection as at 72 with a looper 73. The thrust rod slides in a ball bearing 74 supported by an arm 75 which is pivotally mounted upon an eccentrically adjustable pin 76 whereby the position in space of the ball bearing 74 may be varied to suit the demands of operation of the looper.

A spur gear 77 and a mounting collar on which the gear is removably mounted are removably secured upon the main shaft, the gear operating within and protected by the sleeve boss 24, as shown in Figure 3. The gear 77 meshes with an intermediate idler gear 78 having a ball bearing mounting as at 79 on a stud pin 80 removably secured as at 81 to the flange 23 carried by the standard and arm unit B. The cutout portion 25 of the sleeve boss 24 permits the gears 77 and 78 to mesh, and the casting 33 is provided with

an opening 82 of sufficient size to permit cooperation of said gears.

The intermediate gear 78 imparts rotary motion from the main shaft 21 to a gear 83 secured upon the stub shaft 66 upon which the eccentric 64 and the drunken cam 71 are mounted.

A spring pressed finger 84 is pivoted on the presser foot and projects into the longitudinal slot 52 to hold the fabric stationary during the 10 return movement of the disc.

The casting 33 is open at the bottom, the left side and the rear, and is partially closed by a housing cap 85 which is removably secured by a screw 86 to the web 49. The cap 85 includes 15 a rear recess which is closed by a removable plate 87.

The work support mounting bracket unit D comprises a body 88 which is removably secured upon the base unit by screws 89, and the body 20 has a raised, hollow housing portion 90 which is open at the front, and forwardly extending arms 91 each carrying a bearing 92. In these spaced bearings a pivot shaft 93 is secured, and on this shaft the work support unit E is pivotally 25 mounted to swing downwardly and rearwardly. The unit E is equipped with a cone seat bearing 94 to receive the conical end 95 of the shaft 93. The other end of the shaft 93 is equipped with a 30 conical seat 96 to receive the conical end of a bearing screw 97 which is mounted for projection and retraction in a screw bearing 98 provided in the unit E, as shown in Figure 2 of the drawings.

It will be noted that the work support unit E is 35 pivotally mounted along a line paralleling the main shaft 21 and at a point well in advance of the stitch forming zone. In this manner a relatively large clearance between the work support and the presser foot is provided for by a relatively 40 small amount of depression of the work support.

The work support unit E is provided with a lateral extension 99 underlying the presser foot and at its end this extension supports a pivotally and yieldably mounted work clamp 100 which cooperates with the presser foot.

The work support unit E also carries a ridge-forming element 101 which in this particular disclosure is in the form of an oscillatory disc. The disc is disposed beneath the longitudinal slot 52 in the presser foot and is fixed to a rock shaft 102 supported in bearings 103 provided in the unit E and arranged in parallelism with the main shaft 21. Oscillatory movement is imparted to the shaft 102 and the disc 101 through the 55 medium of a crank 104 secured upon said shaft and having connection with the link 32 which is actuated from the main shaft 21 in the manner hereinbefore described. Depression of the work support is normally opposed by a strong spring 60 designed to permit a yielding movement of the work support away from the presser foot to adapt the machine to operate upon materials of uneven thickness. It is desirable that the operator should not be subjected to the strain incident to depressing the work support against the tension of the 65 heavy spring and for this reason we have provided means for disabling the heavy spring when it is desired to depress the work support for inserting or removing the work. For this purpose the work 70 support unit E is provided with a cup-socket 105 in which operates a vertically movable plunger or support 106 opposed by a heavy coil spring 107 mounted in said socket and providing said strong spring resistance. A reduced portion 108 of the 75 plunger or support 106 extends through an aper-

ture in the work support and carries an enlarged head 109 which operates in a recess formed in the work support and serves to limit the upward movement of the work support E relative to the plunger or support 106 and thereby initially set 5 the work support relative to the presser foot.

The plunger 106 is pivotally connected to the upper one of a pair of upper and lower toggle links 110 which are pivotally connected as illustrated in Figures 5 and 6 of the drawings, and the 10 lower link of which is pivoted as at 111 between the reinforce lugs 10 with which the base unit A is provided. When the toggle links 110 are in vertical alinement with the lower pivot 111 and the plunger 106, the latter is locked and consequently the work support E is locked against full depression, but the work support however is capable of being slightly depressed against the tension of the spring 107 to permit different thicknesses of fabrics and seams passing under the 20 presser foot. An operating link 112 is pivotally connected to the lower toggle link and is reciprocable back and forth within the raised, hollow housing portion 90 of the bracket body by reason of movement of the bell crank lever 113 to one 25 arm of which said operating link is connected. The bell crank lever 113 is pivoted as at 114 to the base lug 11 and has its remaining arm connected by a chain or otherwise to a foot treadle (not shown). It will be readily seen by reference 30 to Figures 5 and 6 of the drawings that by pulling downwardly on the chain 115 the operating link 112 will be thrust forwardly breaking the toggle and pulling the work support downwardly from the position illustrated in Figure 5 of the drawings to that shown in Figure 6.

Intentional depression of the work support by a downward pull upon the chain 115 is resisted only by a relatively light resistance spring 116 which is connected at one end to the bell crank lever 113 40 and at its other end to an adjustable anchor bar 117. The bar 117 is pivotally supported at 118 intermediate its ends on the base lug 13. An adjustable screw 119 engages the other end of the bar 117 and by this means the tension of the 45 spring 116 may be adjusted. An adjustable stop screw 120 is carried by the lower toggle link 110 in position for engaging the adjacent wall of the base recess 9 for limiting the movement of the 50 toggle links in the normal relation of the parts illustrated in Figure 5 against the tension of the spring 116.

In order to vary the spaced relation between the needle and the ridge forming element, we provide a bell crank lever 121 which is pivotally supported upon the pivot shaft 93 and which includes a depending substantially vertical arm and a substantially horizontal and rearwardly extended arm. The vertical arm carries an adjustable stop screw 122 which is engageable with a stop lug 55 on the bracket unit D for determining the position of the work support as indicated in Figure 5 of the drawings. An adjustment lever 123 is pivotally supported intermediate its ends as at 124 in a bifurcation or slotway formed in the rearwardly extended end of the horizontal arm of the bell crank 121, and the rear end of the lever 123 overlies and engages a shelf member 125 which is removably secured to the rear edge of the work support as illustrated in Figs. 5 and 6 of the drawings. The front end of the lever 123 overlies an end of an adjuster bar 126 which is pivoted intermediate its ends as at 127 upon a lug extending laterally from the horizontal portion of the bell crank lever 121. The remaining end of the 70 75

adjuster bar is engaged by an adjuster screw 129 which extends downwardly through a threaded bore provided therefor in the work support E. The work support E is equipped with a recess or well 130 for accommodating the operating knob 131 with which the screw 129 is equipped and through the medium of which the screw may be adjusted for depressing to a greater or lesser extent the end of the adjuster bar 126 with which the screws contact.

It will be readily understood that by turning the knob 131 so as to move the screw downwardly, the bar 126 will be actuated to exert an upward pressure on the forward end of the adjustment lever 123 causing the rear end thereof to be depressed against the shelf member 125 to increase the space between the needle and the ridge forming element and thereby reduce the depth of needle penetration in the fabric. Obviously a movement of the knob 131 in the opposite direction will serve to diminish the space within the limit determined by the limiting head 109 to thereby increase the depth of needle penetration in the fabrics. A light coil spring 132 connected between the front edge of the work support and the vertical arm of the bell crank lever 121 as shown in Figures 5 and 6 of the drawings serves at all times to hold the shelf 125, lever 123, bar 126, and screw 129 in mutual contact.

The adjustment lever 123 pivotally supported in a bifurcation in and extended from the rear end of the horizontal bell crank lever arm, forms a longitudinal extension of that arm and by adjustment of the position of the lever the effective angular relation of the arms of the bell crank is varied. Thus by reason of the contact of the vertical arm with the stop lug on the bracket unit D, and the horizontal arm and its adjustable lever extension with the work support shelf 125 the varying of the effective angular relation of the bell crank arms will vary the spaced relation between the presser foot and the work support.

If desired, a knee-press may be substituted for the treadle and chain equipment 115 and utilized for effecting depression of the work support E. See Figures 17, 18, 19 and 20. The knee-press includes a crank rod 133 to the vertical leg of which is adjustably affixed a knee-press plate 134. The horizontal leg 135 of the rod is pivotally supported in bearings 136 on the base unit A and carries a rigidly affixed crank lever 137, the cam end 138 of which overlies the horizontal leg of the bell crank lever 113 as shown in Figures 18 and 20.

By forcing the knee-press plate 134 to the right, or as shown by the arrow in Figure 17, the crank lever 137 will be depressed and the cam portion 138 thereof will press downwardly upon the horizontal arm of the bell crank lever 113 and impart thereto the same work support depressing movement as would be imparted by use of the chain 115 hereinbefore described.

In the foregoing description we have disclosed a machine composed of a plurality of individually mountable and replaceable standardized units, namely, a base unit, a standard and arm unit, a forwardly extending arm or sewing head unit, a mounting bracket unit, and a work support unit.

By reason of the construction and mounting of the particular work support disclosed and the arrangement of the driving connections in the sewing head, a maximum of feeding room is provided beneath the overhanging arm and the sewing head. This feature of the machine is greatly

aided by the provision of the triple drive gear arrangement in the sewing head including the intermediate gear 18 removably carried by the mounting flange of the standard and arm unit B. As previously stated, the driven gear 83 is carried by the sewing head and the driver gear 17 is removably carried by the main shaft 21 and protected by the sleeve boss 24 of the standard and arm unit B.

It is of course to be understood that the details of structure and arrangement of parts may be variously changed and modified without departing from the spirit and scope of our invention.

We claim:

1. In a sewing machine, work feeding means, a main shaft disposed transversely of the direction of feed of the work, complementary stitch forming means including a reciprocatory needle and a loop taker, a needle drive shaft disposed in right angular relation to the main shaft, means for imparting movement from the main shaft to the needle shaft, a work support extending beneath the stitch forming means, and means for driving the loop taker from the main shaft including intermediate gearing serving to space the sewing zone a considerable distance below the main shaft whereby to provide a maximum of work clearance space.

2. In a sewing machine, work feeding means, a main shaft disposed transversely of the direction of feed of the work, complementary stitch forming means including a reciprocatory needle and a loop taker, a needle drive shaft disposed in right angular relation to the main shaft, means for imparting movement from the main shaft to the needle shaft, a work support extending beneath the stitch forming means, said work support being tiltable about an axis disposed parallel with the axis of the main shaft and spaced a considerable distance in advance of the point at which the stitch forming occurs, and means for driving the loop taker from the main shaft including intermediate gearing serving to space the sewing zone a considerable distance below the main shaft whereby to provide a maximum of work clearance space.

3. In a sewing machine wherein is provided a frame including an overhanging arm and a sewing head supported on the arm, a main shaft rotatably supported in the arm, complementary stitch forming means including a loop taker, and a train of transmission gearing located in the head for imparting movement to the loop taker from the main shaft and serving to space the sewing zone a considerable distance below the arm to provide for a maximum of work clearance.

4. In a sewing machine wherein is provided a frame including an overhanging arm, a main shaft rotatably supported in the arm, a sleeve boss extending longitudinally from said arm, a driver gear secured on the main shaft and rotatable within the boss, a sewing head removably supported on said arm and into which the gear bearing end of the main shaft projects, complementary stitch forming mechanism supported in part in said head and including a loop taker, a stub shaft rotatably supported in the head and having driving connection with the loop taker, and a train of gearing connecting the main shaft gear with the stub shaft.

5. In a sewing machine wherein is provided a frame including an overhanging arm, a main shaft rotatably supported in the arm, a sleeve

boss extending longitudinally from said arm, a driver gear secured on the main shaft and rotatable within the boss, a sewing head, mounting flanges carried respectively by the arm and the head enabling the latter to be removably secured upon the former, an end of the main shaft being projected into said head, complementary stitch forming means carried in part by the head and including a loop taker and a stub shaft rotatably supported in the head and having driving connection with the loop taker, a driven gear secured on the stub shaft, and an intermediate gear meshing with the driver and driven gears and carried by the arm supported mounting flange.

5. In a sewing machine wherein is provided a frame including an overhanging arm, a main shaft rotatably supported in the arm, a sleeve boss extending longitudinally from said arm,

10 a driver gear secured on the main shaft and rotatable within the boss, a sewing head, mounting flanges carried respectively by the arm and the head enabling the latter to be removably secured upon the former, an end of the main shaft being projected into said head, complementary stitch forming means carried in part by the head and including a loop taker and a stub shaft rotatably supported in the head and having driving connection with the loop taker, a driven gear secured on the stub shaft, and an intermediate gear meshing with the driver and driven gears and carried by the arm supported mounting flange,

15 having cut out portions for accommodating the positioning and operation of said gears.

CHARLES W. MUELLER.
HARLEY C. MOULTON.
